US00D868749S

(12) **United States Design Patent** (10) **Patent No.:** **US D868,749 S**
Brunner et al. (45) **Date of Patent:** **** Dec. 3, 2019**

(54) **EARPIECE**(71) Applicant: **Apple Inc.**, Cupertino, CA (US)(72) Inventors: **Robert Brunner**, San Francisco, CA (US); **Christopher Kuh**, San Francisco, CA (US); **Achille Biteau**, San Francisco, CA (US)(73) Assignee: **Apple Inc.**, Cupertino, CA (US)(***) Term: **15 Years**(21) Appl. No.: **29/654,520**(22) Filed: **Jun. 25, 2018****Related U.S. Application Data**

(63) Continuation of application No. 29/595,719, filed on Mar. 1, 2017, now Pat. No. Des. 821,364, which is a continuation of application No. 29/533,509, filed on Jul. 17, 2015, now Pat. No. Des. 780,721, which is a continuation of application No. 29/490,934, filed on May 15, 2014, now Pat. No. Des. 734,744, and a continuation of application No. 29/490,932, filed on May 15, 2014, now Pat. No. Des. 743,945, and a continuation of application No. 29/490,936, filed on May 15, 2014, now Pat. No. Des. 743,946.

Primary Examiner — Paula Allen Greene(74) *Attorney, Agent, or Firm* — Sterne, Kessler, Goldstein & Fox P.L.L.C.(57) **CLAIM**

The ornamental design for an earpiece, as shown and described.

DESCRIPTION

FIG. 1 is a perspective view of an earpiece showing the claimed design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.
